UNITED STATES PATENT OFFICE.

WILLIS M. AMES, OF LOS ANGELES, CALIFORNIA.

DESIGN FOR A FILING-CABINET.

40,270.

Specification for Design.

Patented Sept. 21, 1909.

Application filed May 26, 1909. Serial No. 498,586. Term of patent 14 years.

To all whom it may concern:

Be it known that I, WILLIS M. AMES, a citizen of the United States, residing at Los Angeles, in the county of Los Angeles and State of California, have invented a new, original, and ornamental Design for Filing-Cabinets, of which the following is a specification, reference being had to the accompanying drawing, forming part thereof.

The figure is a perspective view of a filing cabinet, showing my new design.

I claim:—

The ornamental design for a filing cabinet, as shown.

WILLIS M. AMES.
